CLAIM

The ornamental design for a display screen or portion thereof with graphical user interface, as shown and described.

DESCRIPTION

The sole FIGURE is a front view of a display screen or portion thereof with graphical user interface showing the claimed design.

The peripheral dashed broken lines depict a display screen or portion thereof, and form no part of the claimed design. The broken lines within the peripheral dashed broken lines depict portions of the graphical user interface which form no part of the claimed design.

1 Claim, 1 Drawing Sheet
